PUMP

Robert de Stoutz, Zurich, Switzerland

Application April 7, 1934, Serial No. 719,506
In Switzerland April 13, 1933

4 Claims. (Cl. 103—162)

This invention is particularly concerned with mechanical devices designed for use in the manufacture of artificial silk, filaments of which are formed by the extrusion of the cellulose composition through minute orifices from the container in which it is held in a semiliquid or pasty form. It is obviously necessary that the filaments or threads shall be of uniform size throughout their length and that, when it is considered that each filament of thread has a diameter no greater than a few one-thousandths of an inch, a slight irregularity in relative movement of the parts of the mechanism employed in effecting the extrusion of the cellulose composition through the orifice may effect an undesirable variation in the diameter of the filament. The mechanism employed, which is in the nature of a pump and for convenience may be so termed herein, must be so constructed as to provide a free working fit between relatively movable parts and even such a free working fit, measured also in a few thousandths of an inch, unless means to prevent it are provided, may permit such relative displacement of the parts as will be quite sufficient to bring about an undesirable variation in the diameter of the filament. It is therefore the object of the present invention to construct the pump, by which the extrusion of the cellulose mixture through the forming orifices is effected, so as to prevent any such relative displacement of the working parts as might effect a variation in the diameter of the filament. The invention is shown and explained herein as embodied in a pump which comprises a freely floating cylinder block rotated within a housing about its axis without rigid connection with the actuating shaft or member and formed with a plurality of pump cylinders and plungers parallel with the axis of the cylinder block, a cooperating, stationary head formed with channels through one of which a cellulose composition is drawn from the source of supply into each cylinder in turn and from the other of which the composition is forced to and through the orifice of extrusion by the action of each cylinder and piston in its turn. The cylinder block is so held that it cannot be displaced in an axial direction from the cooperating head, more than by the clearance necessary to give a free working fit, and is so subject to the action of pressure devices that, notwithstanding its free fit within the housing, it cannot, under ordinary conditions of operation, be tilted within the housing. The invention will be more fully explained hereinafter with reference to the ac-

companying drawing in which it is illustrated, and in which:

Figure 1 is a view in longitudinal, axial section of an extrusion device or pump constructed in accordance with the invention. 5

Figure 2 is a view of the same in end elevation as seen from the right hand in Figure 1.

Figure 3 is a view in transverse section on the plane indicated by the broken line III—III of Figure 1, and 10

Figure 4 is a view of the same in elevation as seen from above in Figure 1.

The main body 1 of the pump, provided with bearing shoulders 2, is arranged to be secured firmly upon the filament machine, furnishes a 15 suitable bearing for the actuating shaft 3, and is formed with a plane working face 4, the main body 1 thus constituting a working head for co-operation with the cylinder block hereinafter mentioned. The working head is formed in its 20 face with an arc-shaped suction channel 5 which is in communication through a duct 5^a with the source of supply of the cellulose composition, and with a delivery channel 6 which is in communication through a duct 6^a with the extrusion orifice. The container for the cellulose composition and the extrusion orifice may be of usual construction and arrangement and are not necessary to be shown. 25

The shaft 3 is formed at its end with a portion 3^a which is polygonal in cross section and enters with a free fit the corresponding recess in the end of a cylinder block 7, circular in cross-section, which is thus structurally independent of the actuating shaft 3 and, though 35 rotated thereby, is not rigid therewith but floats freely within the housing and has at its plane end face a true but free working contact with the working face 4 of the main body 1. The cylinder block is held in position against the 40 working head through the medium of tension bolts 8 which are engaged with the main body 1, a bridge piece 9, a block 9^a, a ball bearing 9^b, and a spring 10 which is received within the central bore 7^a of the cylinder block and through 45 a washer 10^b bears against a shoulder 7^b of the cylinder block. A housing 11, which is itself independent of the main body 1, receives the cylinder block with a free working fit and is retained by the bolts 8 and bridge piece 9, rotation of the housing being prevented by screws 12 which engage the body 1 and are threaded in the housing 11. The tension bolts 8 have, as shown in the drawing, some clearance in the body 1 and in the bridge piece 9 whereby the 50 55

housing can adapt itself to the cylinder block by which alone it is carried so that no tilting moments can affect the true fit of the cylinder block against the working face 4 of the body 1. 5 The housing and the cylinder block are thus in a manner independent of each other, that is, the one is capable of a limited relative displacement with respect to the other.

In the cylinder block are formed several cylinders 7^c parallel with the axis of the cylinder block and provided each with a long piston or plunger 15. Each piston 15 is formed independently of its head 17 which is received within a carrier 16 supported in the cylinder block and 15 between the left hand end of the carrier chamber and a collar 15^a of the piston is interposed a spring 20 which presses the piston against its head 17 and compensates for wear between the head and a fixed annular cam 13 which is secured to the housing as by means of the block 9^a of which it may form a part and, in the rotation of the cylinder block, at the proper time imparts to each piston 15 through the head 17 its forward or compression stroke. Also secured 20 to the housing adjacent the body 1 is a fixed annular cam 14 which, through slide bars 18, located in longitudinal grooves formed in the periphery of the body 1, and pins 19 which engage the carriers 16 of the pistons 15, effects, at the proper time, the rearward or suction stroke of each piston 15. Each pin projects through the wall of the carrier into a slot 15^b in the head 17 and thereby a limited relative displacement 25 in an axial direction of the head and the carrier is permitted. It will be seen also that through the engagement of each carrier with the pin 19 the pressure of the spring 20 against the left hand end of the carrier chamber serves to press the slide bar 18 against the cam 14. Wear between the cam 13 and the heads 17, on the one hand, and between the cam 14 and the slide bars 18, on the other hand, is thus constantly compensated notwithstanding the fact that the carrier block is itself freely floating. It will also 30 be seen that by this construction each piston has imparted to it by the positive action of the cams 13 and 14 a definite, straight line movement unaffected by lateral forces which would be incident to engagement with wobbling actuators 35 set obliquely with respect to the axis of rotation. It will be understood that in the construction shown, in which five pistons 15 are shown, two at least of the cylinders 7^c are at one time in communication with the suction channel 5 receiving at such time their rearward or suction stroke, and two at least are in turn at the same time in communication with the pressure channel 6, receiving at such time their forward or compression stroke. 40

In the construction shown, all parts being properly formed, the cylinder block is held under yielding pressure against the working face 4, without freedom for longitudinal movement. To prevent any tilting movement of the cylinder block against the working face 4 the cylinder block and the housing are at all times subject to pressure in one direction, a spring 21, received within a seat formed within the housing and bearing against the inner face of the main body 15 serving to exert such constant pressure. The action of the spring 21 may be supplemented by a flat spring 22 secured to the main body 1 diametrically opposite the spring 21 and bearing against the inner face of a plate 22^a secured to the housing. The weight of the housing and

the cylinder block when the axis is horizontal, as is usual, exerts a tilting moment which might result in a one-sided wear of the relatively movable parts, but such tendency is overcome by the provision of the spring 21 between the main body 1 and the housing 11, the tension of the spring being so determined as to balance the tilting movement exerted by the weight of the housing, the cylinder block and the parts carried therewith. The spring 22 compensates not only for the tilting moment but as well for the weight of the cylinder block. 5

As will be appreciated, the utmost accuracy in construction and operation of the mechanism employed in the formation of filaments to be produced is essential to the production of filaments of uniform diameter, and to that end the cylinder block must be held with its plane end face in parallelism with the plane working face of the head so that the interposed film of composition shall be of uniform thickness throughout, the pistons must be actuated by positive means in both directions, lateral components of the piston actuating force, which might tend to displace the cylinder block, must be practically 20 eliminated and compensated, and wear between the pistons and their actuating devices must be compensated constantly. That these results may be accomplished certain features of improvements in the construction and relations of parts 25 of the mechanism have been devised as hereinbefore described and as set forth in the accompanying claims. 30

It will be understood that various changes in details of construction and arrangement, particularly with respect to the means for actuating the cylinder block, may be made without departing from the spirit of the invention, except so far as may be pointed out in the accompanying claims. 40

I claim as my invention:

1. In an apparatus of the character described the combination of a working head with a plane working face having arcuate suction and pressure channels, a cup-shaped housing, a cylinder block rotatable in the housing and having a plurality of cylinders arranged for communication with said channels in the rotation of said cylinder block, pistons for said cylinders, means for reciprocating said pistons in the rotation of said cylinder block, a spring arranged between said cylinder block and the closed end of the housing to press the cylinder block against the working face of the working head, a clearance being provided between the open end of the housing and the working head, tension means taking up the reaction of said spring and limiting the clearance between the housing and the working head with capacity for limited tilting movement of the housing with respect to the working head. 50

2. In an apparatus of the character described the combination of a working head with a plane working face having arcuate suction and pressure channels, a cup-shaped housing, a cylinder block rotatable in the housing and having a plurality of cylinders arranged for communication with said channels in the rotation of said cylinder block, pistons for said cylinders, means for reciprocating said pistons in the rotation of said cylinder block, a spring arranged between the cylinder block and the closed end of the housing to press the cylinder block against the working face of the working head, a clearance being provided between the open end of the housing and the working head, tension means taking up the reaction 60

- of the spring and limiting the interval between the housing and the working head with capacity for limited tilting movement of the housing with respect to the working head, and yielding means effective between the working head and housing to counteract the tilting movement resulting from weight of said housing and cylinder block and thereby prevent one-sided wear of the working face.
5. In an apparatus of the character described the combination of a working head with arcuate suction and pressure channels, a housing, a cylinder block rotatable in the housing and having a plurality of cylinders arranged for communication with the channels in the rotation of said cylinder block, pistons for said cylinders, a suction cam fixed in said housing and in operative relation with the hereinafter named slide bars to effect positively the suction stroke of the pistons, 10 a pressure cam fixed in the housing and in operative relation with the pistons to effect positively the pressure stroke of said pistons, slide bars arranged in the cylinder block in parallelism with the cylinders and cooperating with said suction cam, piston carriers arranged in the cylinder block in alinement with said pistons and operatively connected with the slide bars, the carriers being formed with recesses, piston heads slidably arranged in the piston carriers and cooperating 15 with the pressure cam and the pistons, collars on the pistons, and compressed springs arranged in operative relation with the collars and said recesses to press said pistons against said piston heads and said piston carriers against the slide 20 bars to compensate for wear.
10. 3. In an apparatus of the character described the combination of a working head with arcuate suction and pressure channels, a housing, a cylinder block rotatable in the housing and having a plurality of cylinders arranged for communication with the channels in the rotation of said cylinder block, pistons for said cylinders, a suction cam fixed in said housing and in operative relation with the hereinafter named slide bars to effect positively the suction stroke of the pistons, 15 a pressure cam fixed in the housing and in operative relation with the pistons to effect positively the pressure stroke of said pistons, slide bars arranged in the cylinder block in parallelism with the cylinders and cooperating with said suction cam, piston carriers arranged in the cylinder block in alinement with said pistons and operatively connected with the slide bars, the carriers being formed with recesses, piston heads slidably arranged in the piston carriers and cooperating 20 with the pressure cam and the pistons, collars on the pistons, and compressed springs arranged in operative relation with the collars and said recesses to press said pistons against said piston heads and said piston carriers against the slide 25 bars to compensate for wear.
